UNITED STATES PATENT OFFICE.

WILLIAM L. ROBERTS, OF FREDONIA, PENNSYLVANIA.

CLOTHES-POUNDER FOR WASHING-MACHINES.

952,641.

Specification of Letters Patent. Patented Mar. 22, 1910.

Application filed March 22, 1909. Serial No. 484,960.

To all whom it may concern:

Be it known that I, WILLIAM L. ROBERTS, a citizen of the United States, residing at Fredonia, in the county of Mercer and State 5 of Pennsylvania, have invented a new and useful Clothes-Pounder for Washing-Machines, of which the following is a specification.

This invention relates to clothes pounders 10 for use in connection with washing machines and the like and its object is to provide a device of this character which will operate to quickly clean the fabrics upon which it is used, the pounder being so constructed as to produce a circulation of water 15 through the fabrics during both strokes of the pounder.

Another object is to provide a pounder having combined therewith a yielding 20 presser-plate.

With these and other objects in view the invention consists in certain novel details of construction and combinations of parts 25 hereinafter more fully described and pointed out in the claims.

In the accompanying drawings the preferred form of the invention has been shown.

In said drawings:—Figure 1 is a central 30 vertical section through the pounder. Fig. 2 is a bottom plan view thereof, portions of the pounder being broken away.

Referring to the figures by characters of reference 1 designates the outer frusto-conical shell of the pounder, the same being 35 preferably formed of sheet metal and having its large or open end surrounded by an annular flange 2, while its closed end is provided with a reinforcing head 3 of wood or other suitable material, said head surrounding a tube 4 which extends from the center of the closed end of the shell and is designed to receive the handle 5 of the pounder. 40 Openings 6 extend through the head 3 and register with corresponding openings 7 formed in the closed end of the shell.

Arranged concentrically within the shell 1 is an inner frusto-conical member 8, the 50 large or open end of which is preferably provided with an annular flange 9 disposed in the same plane with the flange 2. The upper or closed end of this member 8 is spaced from the corresponding end of the shell 1 by means of a disk 10 and a reinforcing plate 11 is arranged upon the lower or 55 inner face of the closed end of the member

8 and is secured thereto by means of screws 12 extending through the shell 1 and member 8 and into the head 3. A screw 13 is also arranged within the centers of the member 8 and shell 1 and projects through the spacing disk 10 and into the handle 5, said screw thus serving to hold the handle and the remaining parts of the pounder securely together. Openings 14 are formed within 60 the reinforcing plate 11 and the closed end of the member 8 and register or align with the openings 6 and 7 heretofore referred to. The screws 12 engage the inner ends of spring strips 15, the outer ends of which are 65 secured to the inner face of a presser-plate 16 which is preferably circular. This plate is normally disposed in the same plane with the flanges 2 and 9, but, when subjected to resistance, is designed to move back into 70 the number 8, the spring 15 however serving to promptly return the plate to its normal position after the removal of such resistance.

In using the pounder herein described the 80 same is pressed downwardly against the fabrics contained in a tub or other water-containing receptacle and the flanges 2 and 9 and the presser-plate 16 bear upon the fabrics while the air contained within the shell 85 1 and the member 8 is expelled therefrom through the openings 14, 7 and 6, thus permitting water to pass through the fabrics and into the member 8 and the shell 1. At the same time the presser-plate 16 will be 90 pushed upwardly into the member 8 and against the action of said springs 15. During the reverse stroke of the pounder the fabrics momentarily cling to the shell and the member 8 as a result of the partial vacuum 95 produced therein, and while thus clinging the water contained within the pounder passes back through the fabrics. At the same time the presser-plate 16 operates to push the fabrics outwardly so as to increase 100 the partial vacuum produced during this return stroke, it being impossible for the air to enter the pounder through the openings 6 with sufficient rapidity to promptly displace the water leaving the pounder.

It is of course to be understood that various changes may be made in the construction and arrangement of the parts without departing from the spirit or sacrificing the advantages of the invention.

What is claimed is:—

1. A clothes-pounder comprising inner and

outer hollow members spaced apart annularly and at their upper ends and open at one end, each member having an air vent at its other end, an annular flange upon the 5 open end of each member, connections between the members, a presser-plate, said plate and flanges being normally disposed in the same plane, and springs connected to the marginal portion of the presser plate 10 and to the inner hollow member for yieldingly holding said plate normally in a pre-determined position.

2. A clothes pounder comprising inner and outer hollow members spaced apart annularly and at their upper ends, there being 15 registering vents within said upper ends,

said hollow members being open at their lower ends, a presser plate within and spaced from the open end of the inner member, springs connecting the marginal portion of 20 the presser plate with the closed end of the inner member and annular flanges upon the lower ends of the outer and inner members, said flanges and the presser plate being normally disposed in the same plane. 25

In testimony that I claim the foregoing as my own, I have hereto affixed my signature in the presence of two witnesses.

W. L. ROBERTS.
